UNITED STATES PATENT OFFICE.

BARTHOLD DE MATTIA, OF CLIFTON, NEW JERSEY.

COLLAPSIBLE CORE.

1,389,441.

Specification of Letters Patent. Patented Aug. 30, 1921.

Application filed June 8, 1920. Serial No. 387,416.

To all whom it may concern:

Be it known that I, BARTHOLD DE MATTIA, a citizen of the United States, and resident of Clifton, in the county of Passaic and State of New Jersey, have invented a new and useful Improvement in a Collapsible Core for Use in the Manufacture of Shoes or Casings for Pneumatic Tires.

The object of the present invention is to provide for a maximum freedom of movement of the movable parts or sections so as to facilitate the withdrawal of the movable parts or sections from the shoe or casing and thus facilitate the removal of the shoe or casing without unnecessary distortion.

A further object is to provide a collapsible core in which the key section has such a movement with relation to the other sections that it can be removed from a position of operative continuity to a retracted position in such manner as to afford a greater clearance and freedom of movement of the adjacent movable sections.

A further object is to provide a key section for a collapsible core which, in its movement into and out of operative continuity, may be moved in the plane of the core, and also moved to position it in a plane at right angles to the plane of the core.

To the above ends the present invention consists of a collapsible core comprising a plurality of segmental sections including a key section, said key section being arranged so that it may be positioned in the plane of the core and also in the plane at an angle to the plane of the core, and it further consists of the devices and combinations of devices which will be hereinafter described and claimed.

The present invention is illustrated in the accompanying drawings in which—

Figure 1 shows a top plan view showing in full lines the segmental sections in operative continuity, and in dotted lines, the key section partially retracted.

Fig. 2 shows a vertical sectional view taken on the line 2—2 in Fig. 1.

Fig. 3 is a top plan view illustrating the core in a collapsed condition, the key section being shown in section.

Fig. 4 is a detail, parts being shown in section illustrating the key section in its retracted position and turned so as to ex-

tend in a plane at right angles to the plane of the core.

Similar reference characters will be used throughout the specification and drawings to indicate corresponding parts.

The core is made up of a plurality of segmental sections, there being four sections in the construction as illustrated, consisting of a fixed section 1, a pivoted section 2, a swiveled section 3, and a key section 4.

The fixed section 1 is fixedly secured as by means of the bolts 5 and 6 to the radial arms 7 and 8 projecting from a chuck 9. The chuck 9 is adjustably connected as by means of the bolts 10 and winged nuts 11, to the top of a table 12, the table 12 being pivotally or otherwise supported as at 13 at the outer end of a jack arm 14, and upon its under side near its edge is provided with notches 15 arranged to be engaged by a latch 16 mounted in the jack arm 14 whereby the table, chuck and core may be turned as desired in the operation of building up a shoe or casing thereon.

The segmental section 2 is pivotally connected at 17 to the radial arm 8 and the pivotal connection is preferably such that the section 2 not only has a movement inward and outward with relation to the center, but in its inward and outward movements it will be depressed and elevated in an inclined direction from the pivot 17 to the free end of the section 2, and thus more effectively cooperate with the other sections in securing a maximum collapsing movement of the sections with the core.

The section 3 is a relatively small section and is pivotally mounted at 18 to a swivel 19 which has a bearing in, and is arranged to turn in, a lug 20 carried upon the inner surface of the fixed section 1, as clearly shown in Fig. 1 of the drawings. This construction permits the section 3 not only to have a swinging movement in and out about its pivot 18, but a swiveling movement about the axis of the swivel so that when collapsed it will be dropped downwardly below the plane of the fixed section, as clearly shown in Fig. 3 of the drawings.

Cooperating with these sections 1, 2 and 3 there is a key section 4 arranged to fit between and close the gap in the space between the free ends of the sections 2 and 3, and

2
5 Fig. 1.

thus complete the operative continuity of the core, and the key section is arranged to have a sliding movement into and out of operative continuity, as indicated in dotted lines in

10 Preferably the meeting faces of the key section 4 and the adjacent free ends of the sections 2 and 3 will be cut or formed on slightly converging lines 21 and 22, that is to say, lines which converge from the inner 15 to the outer surfaces so that the key section will have a wedge-like fit between the ends of the sections 2 and 3 and be free at all times to be retracted.

15 The key section 4 is provided upon its inner edge, preferably at the center thereof, with a stem or shank 23 preferably circular in cross section, and mounted to have a sliding movement in a bearing 24 in the chuck 20 9 and held therein by means of a top plate 25 secured to the chuck 9 by means of nuts and bolts 26, the arrangement being such that the shank 23 may not only have a sliding movement in its bearing for the purpose 25 of permitting the key section to be advanced and retracted, but also may be turned in its bearing so that when the key section shall have been retracted to the full extent permitted by the length of the shank 23 it may 30 be turned so as to extend in a direction at right angles to the plane of the core, as indicated in Figs. 3 and 4 of the drawings.

The shank 23 is provided with a series of apertures 27 along its upper surface arranged 35 to be engaged by a pointed hook 28 pivotally connected as at 29 to a lever 30, the lever having at one end a handle 31 and at its opposite end a stud or pintle 32 arranged to be removably engaged with apertured ears 33, 34 and 35 carried by the chuck 40 or the top plate 25, the arrangement being such that when the lever 30 is engaged with the ear 33, the pivoted hook 28 may be engaged with the apertures in the shank 23, for 45 retracting in the shank and key section 4, and the lever 30 may be engaged with the ear 34 so that the pivoted hook 28 may be engaged with the apertured ear 36 on the pivoted section 2, for moving the said section inward, and it may also be engaged with the 50 apertured ear 35 so that the pivoted hook 28 may engage the apertured ear 37 carried by the swiveled section 3 for retracting the said section.

55 Preferably the meeting faces of the sections will be provided with some form of complementary interlocking devices as indicated at 38, 39, 40, 41 and 42 whereby to secure additional rigidity when the parts are 60 in operative continuity.

A set screw 43 is tapped through a threaded bearing in the plate 25 in position to en-

gage the shank 23 so as to lock the shank in its outward position to hold the key section 4 firmly in place and to prevent the shank from turning in its bearing.

In operation, assuming that a shoe or casing has been built up in the usual manner on the core and it is desired to remove it therefrom, the operator first retracts the key section 4 until it clears the space between the sections 2 and 3, and is entirely removed from the shoe or casing. When it shall have been moved backward a sufficient distance the shank 23 is revolved in its bearing so that the key section 4 extends in a plane at right angles to the plane of the core, as indicated in Figs. 3 and 4 of the drawings after which the pivoted section 2 and the swiveled section 3 are swung inwardly and 80 in the case of the swiveled section, downwardly, as indicated in Fig. 3, after which the shoe or casing may be stripped from the fixed section 1.

Having described my invention, I claim: 85

1. A collapsible core comprising a plurality of segmental sections, including a key section, means for moving the key section into and out of operative continuity in the plane of the core, and means for moving the 90 key section when retracted about a radial axis so as to position it in a plane at right angles to the plane of the core.

2. A collapsible core comprising a plurality of segmental sections, including a key section, a shank or stem carrying said key section, and a bearing in which the shank or stem has a sliding and turning movement.

3. A collapsible core comprising a plurality of segmental sections, including a key section, a shank or stem carrying said key section, a bearing supporting the shank or stem so that it has a sliding and turning movement therein, and means for locking 105 the shank or stem in its bearing.

4. A collapsible core comprising a plurality of segmental sections, including a key section, a shank or stem circular in cross-section carrying said key section, a bearing in which said shank or stem has a sliding and turning movement, a series of apertures in said shank or stem, and means coöperating with the apertures to retract the key section.

5. A collapsible core, comprising a fixed section, a pivoted section, a swiveled section and a key section, means to move the key section into and out of operative continuity in the plane of the core, and means to turn the key section at an angle to the plane of the core when retracted about a radial axis.

BARTHOLD DE MATTIA.
